COIN SELECTOR

Bert E. Mills, Oak Park, Ill., assignor to Mills Novelty Company, Chicago, Ill., a corporation of Illinois

Application October 1, 1937, Serial No. 166,765

4 Claims. (Cl. 194—101)

This invention relates to coin selectors of the material-testing type employing a magnetic field, and has as its object to provide a selector for separating Canadian nickels from other types of 5 coins and slugs.

Canadian nickels have a high nickel content. Nickel is sufficiently magnetic to be classed as a paramagnetic substance, although it is not as 10 strongly magnetic as iron or steel. Accordingly, the chief purpose of the present invention is to provide a selector which will effect a separation between paramagnetic coins, slugs, etc. of varying magnetic quality, as well as effecting separation 15 between paramagnetic coins and diamagnetic or non-magnetic coins, slugs, etc.—that is, the Canadian nickels must be selected from both coins and slugs having stronger magnetic properties and coins and slugs that are diamagnetic or non-magnetic.

20 To this end, the invention provides an arrangement in which the coins and slugs are rolled past a magnet which allows the diamagnetic or non-magnetic coins, slugs, etc. to continue past, in a relatively straight path, which swings the Canadian coins out of said path into a path substantially at right angles thereto, but allows them to pass on, and which completely stops and holds the iron and steel slugs.

I have discovered that by positioning a magnet so that the coins may roll in direct contact with one of its poles, such separation may be effectively attained. The most successful arrangement is one in which a coin rolls against the end face of a pole, said end face forming the 25 bottom of an inclined passage for confining the coin in an upright position. Another effective, although less efficient, arrangement is one in which the side face of the pole forms the bottom of the inclined passageway.

30 Another object of the invention is to provide means for adjusting the strength of the magnetic field so as to properly adjust the balance between the diverting effect of the magnet on the Canadian nickel and the arresting effect upon the iron and steel slugs. It will be understood in this connection that if the magnetic field is too strong, the Canadian nickels, as well as iron slugs, may be 35 completely stopped, whereas if the field is too weak, iron slugs, as well as Canadian nickels, may pass on into the Canadian nickel outlet.

35 Other objects of the invention will become apparent from consideration of the following detailed description of the invention in connection with the accompanying drawings, in which:

Figure 1 is a front elevation of a coin selector embodying the invention;

Figure 2 is a vertical, longitudinal, sectional view of a portion of the same;

Figure 3 is a rear elevation of the same;

Figure 4 is a vertical, transverse, sectional view, taken on the line 4—4 of Figure 3;

Figure 5 is a similar view, taken on the line 5—5 of Figure 3; and

Figure 6 is a detailed perspective view of the 10 magnet, the adjusting block, and a coin rolling on the magnet.

A selector constituting an illustrative embodiment of the present invention is shown in the drawings and includes a vertical base plate 10 15 which carries the various passage-forming and control members. Mounted in an opening 11 in the plate 10, is an elongated horseshoe magnet 12, its poles 13 and 13a projecting upwardly. The longitudinal axis of the magnet 12 is somewhat 20 inclined from the horizontal so that the upper face 14a of its pole 13a may form a portion of the bottom of an inclined passage 15 down which the coin 16 is adapted to roll. The remainder of the bottom of said passage is formed by a block 17 25 secured at 18 to the plate 10, and the sides of the passage are formed respectively by the plate 10 and a scavenger gate 18.

The coins enter the passage 15 through a vertical passage 19 extending downwardly from the 30 coin inlet 20.

Beyond the lower end of the magnet 12, the passage 15 branches into two passages, one of which is indicated at 21 and extends downwardly along the end of the pole 13a, said passage 21 35 being formed between the end of the pole 13a, the plate 10, the side wall of the coin chute indicated at 22, and an upturned portion 23 of a bottom flange 24 of said chute 22. The chute 22 bends laterally beneath the magnet 12 and conveys the accepted coins to an outlet 57.

The other of said branching passages is marked 25 and extends beyond the passage 21, between the plate 10, the lower end 26 of a scavenger chute 27, and the upturned portion 23 of the 45 flange 24. The passage 25 receives the diamagnetic coins, which, in rolling through the passage 15, obtain sufficient momentum to jump over the passage 21 in a trajectory indicated by the broken line 28.

The passage 25 also receives iron and steel slugs which are arrested by the magnet and held in the passage 15 in the position indicated at 29 until subsequent operation of the machine causes said coins to be kicked off the magnet into the 50 55

scavenger chute 27 by scavenger mechanism, which will hereinafter be more fully described. At this point, it may be noted that the scavenger chute 27 lies in a plane offset laterally from that of the acceptable coin receiving chute 22, and from the flange 23 upwardly to the upper end of the scavenger chute a partition wall 56 (Figure 4), formed as a continuation of the outer wall of the chute 22, separates the chute 27 from the passages 15 and 21.

Canadian nickels, as they roll along the face 14a of the magnet, will be slowed down and caused to follow downwardly along the end face 30 of the pole piece 13a as indicated by the broken line 31. Thus the Canadian nickels will be caused to travel through the passage 21 into the acceptable coin receiving chute 22.

I find that sufficient magnetic attraction between the coins and the magnet can be secured by allowing the coins to roll in direct contact with the end face of the elongated pole of the magnet, so that weakly paramagnetic coins, such as Canadian nickels, may be caused to follow around the end of the magnet and be thus diverted out of the trajectory which carries the diamagnetic coils across the gap at the upper end of the passage 21 and into the passage 25, and to completely arrest all highly paramagnetic slugs, such as those of iron and steel.

It is also possible to secure such separation by rolling the coins against the side faces 32 of the magnet, the magnet being positioned with this side uppermost, but such arrangement is not as effective as that shown.

The magnet 12 is mounted in a U-shaped bracket 33 having end portions 34 and 35 and ears 36 and 37, by means of which the bracket is secured at 38 to the plate 10. The magnet is clamped between the end portions 34 and 35 by means of a bolt 43 which extends between the poles of the magnet.

The end portion 35 is extended upwardly as at 39. A block 40 of iron or steel is adjustably secured by means of a screw 41 passing through a slot 42 in the extension 39 and threaded into said block. By loosening the screw 41, the block 40 may be adjusted transversely of the pole faces 14 and 14a. Normally, it extends across the pole face 14 and partly across the pole face 14a, leaving a space through which the coin 16 may pass. The width of this space and the width of the area of contact between the block and the face 14a, determine the strength of magnetic attraction between the coin and the magnet, since said block 40 serves to short the magnetic flux of the magnet proportionately to such area of contact. The greater the area of contact, the more the magnetic field is reduced at the upper end of the magnet.

It may be noted at this point that the adjusting block is located at the upper end of the magnet so that it exerts a controlling effect upon the retardation of the coin in the early stages of its travel upon the magnet, but has little or no effect upon the divergence of the Canadian nickels around the lower end of the magnet or the arresting effect of the lower end of the magnet on the iron and steel slugs. I find that the selectivity of the device can be much better adjusted with this arrangement than if attempt were made to vary the strength of the magnetic field at the lower end of the magnet.

The scavenging mechanism for dislodging the iron and steel slugs comprises a kicker 44 pivoted at 45 to a bracket 46 mounted on the plate

10, said kicker having a foot 47 which projects through the opening 11 just above the faces of the magnet. The upper end of the kicker 44 projecting above the pivot 45 at 48, is engaged by a cam 49 mounted on a shaft 50 journaled in ears 52 of the plate 10, and having a lever 53 carrying a pin 54 adapted to be connected to suitable operating mechanism. Oscillation of the shaft 50 causes the cam 49 to engage the extension 48 and cause the kicker 44 to move from the dotted-line position to the position shown in full lines in Figure 5, whereupon the foot 47 will push the steel slug 55 from the magnet into the scavenger chute 27.

The foregoing detailed description has been given for clearness of understanding only, and no unnecessary limitations should be understood therefrom, but the appended claims should be construed as broadly as permissible in view of the prior art.

I claim as my invention:

1. In a coin selector for paramagnetic coins, means for effecting separation of coins of intermediate paramagnetic qualities from slugs of higher paramagnetic qualities comprising a selector chute adapted to receive coins to be tested, a horseshoe magnet the pole faces of which are elongated in a direction perpendicular to the plane of the magnet, one of said faces extending longitudinally of said selector chute and forming the bottom therefor, said face being substantially longer than the diameter of a Canadian five-cent coin, a discharge chute adjacent said magnet for receiving coins which are substantially retarded by the magnet, and a second discharge chute for receiving coins which are not substantially retarded by the magnet.

2. In a coin selector for paramagnetic coins, means for effecting separation of coins of intermediate paramagnetic qualities from slugs of higher paramagnetic qualities comprising a selector chute adapted to receive coins to be tested, a horseshoe magnet having pole faces which are elongated in a direction perpendicular to the plane of the magnet, one of said faces extending longitudinally of said selector chute and forming the bottom therefor and being inclined slightly from the horizontal in a lengthwise direction, said face being substantially longer than the diameter of a Canadian five-cent coin, a discharge chute adjacent said magnet for receiving coins which are substantially retarded by the magnet, and a second discharge chute for receiving coins which are not substantially retarded by the magnet.

3. In a coin selector for paramagnetic coins, means for effecting separation of coins of intermediate paramagnetic qualities from slugs of higher paramagnetic qualities comprising a selector chute adapted to receive coins to be tested, a horseshoe magnet the pole faces of which are elongated in a direction perpendicular to the plane of the magnet, one of said faces extending longitudinally of said selector chute and forming the bottom therefor, said face being substantially longer than the diameter of a Canadian five-cent coin, a discharge chute adjacent said magnet for receiving coins which are substantially retarded by the magnet, a second discharge chute for receiving coins which are not substantially retarded by the magnet, and scavenging means for removing from the selector chute slugs or like articles which are arrested by said magnet, and for causing discharge thereof from the device.

4. In a coin selector for paramagnetic coins, means for effecting separation of coins of intermediate paramagnetic qualities from slugs of higher paramagnetic qualities comprising a selector chute adapted to receive coins to be tested, a horseshoe magnet the pole faces of which are elongated in a direction perpendicular to the plane of the magnet, one of said faces extending longitudinally of said selector chute and 10 forming the bottom therefor, said face being substantially longer than the diameter of a

Canadian five-cent coin, a bridge of conductive material extending between the pole faces of said magnet and being adjustable to vary the magnetic attraction of the latter upon the coins, a discharge chute adjacent said magnet for receiving coins which are substantially retarded by the magnet, and a second discharge chute for receiving coins which are not substantially retarded by the magnet. 5

BERT E. MILLS. 10
